UNITED STATES PATENT OFFICE.

AUGUSTUS GALNY, OF GALVESTON, TEXAS.

ABDOMINAL SUPPORTER.

SPECIFICATION forming part of Letters Patent No. 284,831, dated September 11, 1883.

Application filed February 8, 1883. (No model.)

To all whom it may concern:

Be it known that I, AUGUSTUS GALNY, of Galveston, in the county of Galveston and State of Texas, have invented a new and Improved Gestator Abdominis, of which the following is a full, clear, and exact description.

My invention consists of an abdominal sack for the support of the abdomen in pregnancy, which is contrived with supporting bands 10 adapted for supporting it from the shoulders of the wearer, where the weight can be best sustained, and so as to entirely avoid the belt commonly used, and thus relieve the stomach and liver from the pressure and irritation which 15 it produces, all as hereinafter fully described.

Reference is to be had to the accompanying drawings, forming part of this specification, in which similar letters of reference indicate corresponding parts in both the figures.

Figure 1 represents my improved abdominal supporter in front perspective view of the person of the wearer as it is applied in use. Fig. 2 is a rear perspective of Fig. 1.

The bandage *a*, which is of the usual form 25 of the abdomen, so far as the front is concerned, is elongated and reduced in breadth at the hips to the form of straps *b*, which pass over the hips and cross the back of the patient to the opposite shoulders, the two straps also crossing each other at the middle of the back, or 30 thereabout, and descending from the shoulders along the sides of the breast of the wearer to the sack, to which they are connected by branched straps *c*, buckled to them at *d*, for 35 lengthening and shortening them as required.

I propose to arrange pads *e*, of soft material, under the straps *c* and the buckles, and along the region of the breasts will construct the straps *b* with suitably-rounded edges, *f*, and of suitably soft material, for protecting them from irritation. The front straps, *c*, will be elastic, in part, to permit full action of the body. By means of this arrangement of the straps *b* the gestator cannot slip out of position, as tension in front to raise the abdomen will also draw the lower part of the bandage toward the back part of the body by the tension across the hips. Besides affording comfortable support of the abdomen and preventing accidental injury to persons requiring to use it, it will prevent prolapsus uteri and abortus. It adjusts and forms 45 itself naturally and comfortably around the lower abdomen, and prevents much of the pain usually suffered by pregnant women, and the bandage can be applied over the under-garments with like useful results, if desired. 50

Having thus fully described my invention, I claim as new and desire to secure by Letters Patent—

An abdominal sack, *a*, having elongations 60 forming straps *b*, which pass over the hips across the back, over the shoulders, and down the breast to the front, and being connected to the front *a* by buckles *d* and straps *c*, substantially as described.

AUGUSTUS GALNY.
